[57] CLAIM

The ornamental design for a chest, as shown and described.

DESCRIPTION

FIG. 1 is a front perspective view of a chest showing our new design;

FIG. 2 is a left side elevational view, the opposite side being a mirror image thereof;

FIG. 3 is a front elevational view thereof;

FIG. 4 is an enlarged partial top left side perspective view thereof; and,

FIG. 5 is an enlarged partial bottom front and left side perspective view thereof.

The broken line showing of environmental elements is for illustrative purposes only and forms no part of the claimed design.

The bottom, top and rear views (not shown) form no part of the claimed design.
